Application April 2, 1949, Serial No. 85,219

20 Claims. (Cl. 53—136)

1

This invention relates to a packaging machine of the general type wherein a plurality of articles are adapted to be arranged or inserted in a container of a preferred form.

The primary object of the present invention is the provision of new and novel means for packaging a plurality of articles in a predetermined type of container so that a part of the article at each end of the container will project a predetermined distance beyond the confines of the container and all the articles so contained will be locked in position.

Another important object of the invention is the provision of a machine for inserting a plurality of articles having the upper and lower ends thereof provided with an upstanding arcuate rim adapted to be engaged by an integral tongue on the container, whereby a plurality of articles may be inserted in the container and then locked in position by the tongue on the container engaging the arcuate outstanding rim.

A still further object of the invention consists in inserting a plurality of cans in a container of a predetermined kind, the container being provided with integral tongues which are folded back during the insertion of the cans in the container and then engage the outstanding annular rim of the container so as to lock the end cans in position in the container, additional cans being maintained in the container between the end locked cans.

A still further object of the invention resides in the provision of a new and improved machine for inserting a plurality of articles in an open ended container of a preformed type, at least one article being inserted in one end of the container and at least one other article being inserted in the container from the opposite end, the container having integral tongues adapted to engage in the countersunk ends of the articles, which countersunk ends are each defined by an outstanding annular rim, there being spreader fingers to spread the ends of the container a distance sufficient to permit the cans to slide easily in place.

Still another object of the invention is the provision of a new and improved method for packaging articles in a container which consists in spreading apart one end of an open ended container a predetermined distance, inserting one or more cans in the spread open end of the container and then later spreading the opposite end of the container and inserting additional articles in the latter open end of the container.

Numerous other objects and advantages will be apparent throughout the progress of the specification which follows.

The accompanying drawings illustrate a certain selected embodiment of the invention, and the views therein are as follows:

Fig. 1 is a fragmentary plan view of one end of a packaging machine embodying the invention;

Fig. 2 is a detail longitudinal sectional view on the line 2—2 of Fig. 1, the can about to be in-

serted in the container being omitted for the sake of clearness;

Fig. 3 is a detail transverse sectional view on the line 3—3 of Fig. 1;

Fig. 4 is a detail transverse sectional view on the line 4—4 of Fig. 1;

Fig. 5 is a view similar to Fig. 4 but showing the spreader fingers in operating relationship and the plunger or pusher member positioning the cans in the container;

Fig. 6 is a detail sectional view on the line 6—6 of Fig. 1, but showing two additional cans inserted in the container;

Fig. 7 is a detail sectional view showing the manner in which the integral locking tongues on the carton are engageable with an outwardly projecting annular rim at the end of a can; said view being taken on the line 7—7 of Fig. 9;

Fig. 8 is a detail plan section on the line 8—8 of Fig. 5;

Fig. 9 is a detail plan section on the line 9—9 of Fig. 6;

Fig. 10 is a detail perspective view of a modified form of container which is adapted to be used;

Fig. 11 is a detail perspective view of the container shown in Figs. 1—9, inclusive; and

Fig. 12 is a detail perspective view of the container having four cans locked in position therein.

The particular cartoning machine herein shown for illustrating the invention comprises a suitable supporting structure 1, such as the frame of the machine, which supports a movable central conveyor 2 adapted to support and convey a plurality of spaced apart cartons or containers 3, Fig. 1. The conveyor 2 for supporting and conveying the cartons 3 comprises a central stationary lower plate 4; Figs. 1 and 3, supported by supporting means 5, Fig. 3, which are secured to a rigid part of the machine frame or support 1. A pair of chains 6 are arranged on opposite sides of the central plate 4 and are trained over suitable sprockets on opposite ends of the machine, said sprockets being arranged so as to move each chain in a continuous orbital path. Each chain 6 carries a plurality of upstanding arms or fingers 7 which are adapted to push the cartons 3 and slide the cartons along the plate 4. The driving sprockets which drive the chain 6 may be operated by any convenient mechanism to move the chains intermittently so that there will be a rest or dwell at certain positions to permit articles to be inserted into the cartons. One form of means which may be used for intermittently driving the chains 6 may be a Geneva wheel. A stationary upper plate 8 may be provided above the conveyor 2, this upper plate being spaced above the lower plate 4 at a height sufficient to permit the cartons 3 to be pushed therebetween so that empty cartons on the conveyor may not collapse before they reach certain carton loading positions hereinafter more fully described.

A first article conveyor 9 is arranged along

one side of the central article conveyor 2 and is adapted to convey a plurality of articles 10 in double rows, Fig. 1, to a predetermined position at a discharge station where a pair of the articles 10 may be inserted into one end of a container 3. The conveyor 9 may comprise an endless belt 11 trained over end rollers 12 which are driven by sprockets 13 over which a chain 14 is trained. The article conveyor 9 is adapted to convey two rows of articles 10 and deposit them on a dead plate or stationary member 15, Fig. 1, which is arranged at the end of the article conveyor 9. A stop plate 16 is arranged at the end of the article conveyor 9 and in the path of the end two articles 10. The stop plate 16 is adapted to stop the articles in a predetermined position so that they may be positioned in a carton 3 which is at rest or at dwell position directly opposite the plate 15.

A second article conveyor 17 is mounted on the opposite side of the central container conveyor 2 and is adapted to convey two rows of articles 10 to a predetermined position to be inserted in a carton 3 at the opposite end of the carton. The article conveyor 17 is identical in all respects with the article conveyor 9 and comprises an endless belt 18 which is trained over end rollers 19 and driven by sprockets 20 over which a sprocket chain 21 is trained. A dead plate or stationary member 22 is arranged at the end of the conveyor 17 to receive a pair of articles 10. A stop plate 23 is arranged in the path of the conveyor 17 so as to hold and support a pair of articles 10 on the plate 22 so that the articles 10 may be inserted at the opposite end of the container 3.

The container 3 is preferably an elongated cardboard carton rectangular in cross sectional shape as shown in Fig. 11, and is adapted to contain four articles 10. The articles 10 are regular cylindrical cans having depressed or countersunk ends 24, Figs. 7 and 12, defining an outstanding annular flange 25. The container or carton 3 is shown as being elongated vertically and comprises opposite side walls 26, 26 and opposite top and bottom walls 27, 27. The carton is open at its ends but has extending therefrom at each end integral outstanding tongues 28. The integral tongues 28 are adapted to be bent downwardly and inwardly from the position shown in dotted lines in Fig. 11 to the position of vertical alignment with each other shown in full lines, so that the cans 10 as they are to be inserted in the carton or container 3 will engage these tongues 28 and force them inwardly against the inside surface of the top and bottom walls 27, so that when a can 10 is inserted in the end the tongues or flaps 28 will be arranged in the annular recess 24 in the top and bottom of the cans and be engaged by the annular rim or bead 25 whereby the end cans will be locked in position. The carton may be of any sufficient length but is shown herein as supporting or containing four cans. However, the carton may be longer so that more cans may be arranged in alignment therein, or the carton may be shorter to support or carry only two cans. Also the container may be of the multiple section type such as shown in Fig. 10, and incorporate cartoning sections or openings 29 and 30. The width of a section 29 or 30 is substantially the same as the width of the carton 3, the width of the carton being determined by the diameter of the can 10. The height of the carton 3 is substantially equal to the height of a can. Each section 29 and 30 of the carton shown

in Fig. 10 is as wide as a can and is as high as a can. The length may be that desired to carton two or more cans, and there may be more sections than shown in Fig. 10. There may be three sections to accommodate three cans each, or there may be three sections to accommodate four cans, or there may be two sections for one can each. The one section container 3 may be for two or more cans, four being shown for the purpose of convenience.

The machine of the invention is adapted to insert the cans 9 in the container 3; two cans are first inserted in one end of the container and then later two more cans are inserted in the other end of the container. It is difficult to insert the cans in the containers properly because the containers should be of a size just sufficient to receive and support the cans. If the containers are too large the tongues 28 on the containers may not register properly with the rims of the can or they may come out of registration. It is therefore desirable that the container or carton fit snugly about the cans. To have the carton fit snugly about the cans and to permit easy and proper insertion of the cans in the carton, it is desirable that the ends of the carton be spread or bowed out somewhat so as to permit the cans to slide easily into place.

The means for spreading apart the opposite walls 27 of the container at one end thereof for the insertion of two cans from the article conveyor 8 comprises a spreader member 31, Figs. 1, 2, 4 and 5. This spreader member 31 comprises a frame 32 to which a plunger rod 33 is connected, the plunger rod being slidably mounted in suitable guides carried by the frame of the machine whereby the frame 32 is adapted to have shiftable movement in a direction at right angles to the direction of the conveyor 2. The shiftable movement is effected in proper timed relationship with the movement of the cans and the position of the carton when it is at rest or in its dwell position. The movement of the plunger rod 33 may be operated or controlled by any convenient mechanism such as by a cam (not shown).

The frame 32 comprises a vertical member 34 to which upper and lower legs 35 and 36, respectively, are connected, being preferably made integral therewith. The frame 32 of the spreader member 31 carries elongated spreader fingers 37 and 38 which are pivoted at 39 and 40, respectively, to the parts 35 and 36. The fingers have arcuate outer surfaces and are elongated and relatively thin at their extreme outer ends. As the spreader 31 moves inwardly (to the left, Fig. 4) the fingers will engage the tongues 28, and when the cans 10 are pushed into the container by means of an article pusher 41, the cans will ride on the inner arcuate surface 42 of the fingers 37 and 38, whereby the tongues 28 will be moved inwardly against the top and bottom walls. The upper and lower walls of the container are caused to be spread apart a predetermined distance by the fingers 37 and 38 as a pair of cans 10 are being fed into one end of the container. A vertical stationary side plate 43, Figs. 1, 3, 4 and 5, which is rigid with the machine frame may be provided between the conveyor 2 and the conveyor 17 to prevent the carton which is being filled from being pushed off of the conveyor 2 while the cans are being pushed or inserted therein. The cans are preferably pushed into the container by the pusher 41 or plunger 41 a predetermined distance but the

can in contact with the pusher should be pushed into the container a distance not greater than the length of a flap or tongue 28, as shown in Figs. 5 and 8. When the spreader 31 has operated to move toward the container and the plunger 41 has been operated to push two cans in the container as shown in Fig. 8, the plunger 41 will retract, whereupon the spreader will also retract, pulling the fingers 37 and 38 out of the container. Springs 44 are attached to the spreader fingers 37 and 38 to return them to their normal position, Fig. 4, after the plunger has retracted a predetermined distance. The springs 44, Fig. 4, then hold the fingers 37 and 38 in their normal position so as to be engaged by the cans as they are being pushed by the plunger 41. The plunger 41 is operated in timed relationship with the spreader member 31 and may be operated by any convenient means such as by a cam (not shown). The two cans 10 on the conveyor 9 are adapted to be inserted in one end of the container 3 at the time the container is in its rest or dwell position between its intermittent movements.

Two cans from the conveyor 17 are adapted to be inserted in the opposite end of the container 3, and to cause the insertion of these latter two cans there is provided a second spreader member 45, Figs. 1 and 6. This spreader member 45 is identical in all respects with the spreader member 31 and comprises a frame 46 including a vertically extending member 47 and upper and lower legs 48 and 49, respectively. An upper spreader finger 50 is pivotally mounted to the upper leg 48 and a lower spreader finger 51 is pivotally mounted to the lower leg 49. A plunger rod 52 is adapted to shift the spreader member 45. Springs 53 are provided so as to return the spreader fingers 50 and 51 to their normal positions when the spreader member 45 retracts away from the carton.

The first two cans from the conveyor 9 are inserted in the container 3 at the position indicated at 54, Fig. 1, and two cans 10 on the article conveyor 17 are adapted to be inserted in the opposite end of the container when the container has moved to an advanced position indicated at 55, Fig. 1. At this latter position 55, the container again comes to a rest or dwell, and when it is at this rest position the spreader member 45 moves toward the carton, as viewed in Fig. 1, and a second plunger 56 pushes two cans 10 on the support 22 into the unfilled end of the container, the spreader member 45 moving toward the carton so that the spreader fingers 50 and 51 will be in a position to spread apart the opposite walls 27 of the container at the end being filled. The plunger 56 will push the cans from the dead plate 22 into the carton, and while it is very possible that the original two cans were inserted deeper than necessary, as shown in Fig. 8, the cans being pushed by the plunger 56 will push them back to final position, whereupon the container will have four cans in the position shown in Fig. 9. The spreader member 45 is then retracted outwardly, thereby causing the spreader fingers 50 and 51 to be withdrawn from their interposed positions between the end can and the tongues or flaps 28. A stationary stop plate or bar 57 which is rigid with the machine frame may be provided at the end of the carton opposite the end into which the last two cans are inserted. This stop plate or bar 57, like the plate 42, prevents the carton from being pushed

off the conveyor 2 while the last two cans are being pushed or inserted into the carton.

When all four cans are in place the tabs or tongues 28 on the top and bottom of the container and at both ends will be in a position to be received in the countersunk top or bottom ends 24 of the containers, and the outer edges of these tongues or flaps 28 will engage behind the rim 25. Therefore, the two end cans 10, Fig. 9, will be locked in place by the upper and lower tabs 27 at each end of the carton. The size of the carton is such that when the cans are in the position shown in Fig. 9 there will be very little if any space between the cans. Therefore, the cans will be completely locked in place in position in the container, and cannot be removed until the container is broken or a tool is inserted between an end of the can to lift a flap 28 out of the recess 24 and away from the rim 25 so as to permit the can to be removed. When the cans are in position in the container and the flaps are in the countersunk surfaces 24, and against the rim 25, a unitary package is formed whereby the container may be turned end for end, side for side, or in any direction, and it is impossible to remove the cans. Moreover, in order to pull out a can a very considerable force has to be applied because the tabs or tongues 28 will be in the position shown in Figs. 9 and 7; that is, they will be doubled back against the outer surface of the container and held in confined position between the inside upper and lower walls of the container and the outer upper and lower walls of the can.

Operation

Cans are fed in double rows by the conveyors 8 and 16. The last two cans of each conveyor are supported on a dead plate and held in position by a stop plate. When the carton arrives in position as indicated at 54 in Fig. 1, the spreader 31 will move inwardly a slight distance, whereupon the plunger 41 will push the two cans on the dead plate into one end of the carton, the fingers 37 and 38 having spread the opposite walls 27, 21 of the carton a sufficient distance to permit the cans to be inserted easily. As soon as the two cans are inserted, the plunger will retract and the spreader 31 will retract, whereupon the cans will be in the position shown in Fig. 8. The carton conveyor 2 will then resume its intermittent movement until the carton reaches the position shown at 55, Fig. 1. The spreader 45 then holds the upper and lower surfaces of the carton apart to permit the plunger 56 to push two more cans in place, whereupon the cans will be positioned in the carton as shown in Fig. 9. In this latter position the tongues or flaps 28 at the upper and lower walls of the container and at each end thereof will be in a position so that the flaps will drop in the indented surfaces 24 at the top and bottom ends of the cans positioned at the opposite ends of the carton, with the outer edges of the tongues or flaps 28 in engagement with the rim 24 of these cans. The four cans will thus be slightly locked in position in the carton whereby a unitary carton containing four cans is provided.

The cartons as previously mentioned may be of such a size as to accommodate only two cans, and in such a case there will be one can positioned first from the conveyor 9 and the second can from the opposite end of the conveyor 17. Should the carton be designed to accommodate three cans, two may be inserted from one end from the con-

veyor 9 and one from the conveyor 17. Should it be desirable to carton six cans it may be done by inserting three in line on the conveyors 9 and 17 instead of two each from those conveyors. If desired the carton may be constructed in two or more sections as shown in Fig. 10. Each section may contain two, four or six cans and there may be one, two or more sections.

The invention provides a machine which comprises continuously operating belts for moving the cans to discharge stations; two cans are first inserted in one end of the container, and the container then moves forwardly to a further station where two additional cans are inserted in the opposite ends of the container. After the cans are in position in the container as shown in Fig. 9, the continuous operation of the carton container will discharge the articles to a proper discharge station, such as a conveyor.

The invention therefore provides a very simple mechanism which is efficiently operated. It has been found that at least 300 cans may be cartoned a minute by adapting the construction herein shown and described.

Changes may be made in the form, construction and arrangement of the parts without departing from the spirit of the invention or sacrificing any of its advantages, and the right is hereby reserved to make any and all such changes as fall fairly within the scope of the appended claims.

The invention is hereby claimed as follows:

1. A packaging machine comprising an intermittently movable carton conveyor having a dwell period for momentarily retaining an open ended carton at a filling station, means to move an article to a discharge position in register with an open end of the carton at the filling station, spreader means to spread the open end of the carton body at said filling station, and pusher means to push an article from said discharge position into the carton body when the spreader means maintains the open end of the carton body in spread condition, said spreader means entering the carton body and being actuated by the article to be inserted into the carton.

2. A packaging machine comprising an intermittently movable carton conveyor having a dwell period for momentarily retaining an open ended carton at a predetermined carton loading position, means to move an article to a discharge position in register with an open end of the carton at said loading position, a retractable spreader member movable from a retracted position to carton engaging position when a carton assumes its loading position to deform the carton to increase the size of the carton in one direction, and a retractable plunger movable to push an article from the article conveyor into the carton while the spreader member is in its carton engaging position, said spreader member entering the carton body and being moved by said article to spread said carton.

3. A cartoning machine for packaging articles in open-ended cartons comprising an intermittently movable carton conveyor adapted to move a series of open-ended cartons successively to a loading station and to momentarily retain said articles at said station for loading purposes, a movable article conveyor adapted to move a series of articles successively to a discharge position in register with a carton at said loading station, a spreader member movable from a retracted position to an advanced position in close proximity to the cartons at said loading station, opposed

spreader fingers on said spreader member movable from retracted to carton engaging and spreading positions when the spreader member is in its advanced position, said spreader fingers being movable into the carton body and being positioned in the path of movement of articles as they move into the open ends of the cartons when the spreader member is in its advanced position whereby engagement thereof with the articles causes them to move to their spreading positions, and a retractable pusher for pushing the articles from the article conveyor into the cartons.

4. A cartoning machine for packaging articles in open-ended cartons comprising an intermittently movable carton conveyor for moving a series of open-ended cartons successively to a loading station, a movable article conveyor for moving a series of articles successively to a discharge position in register with a carton at said carton loading station, a retractable spreader member movable between advanced and retracted positions toward and away from the carton at said loading station, opposed spreader fingers movably mounted on the spreader member and receivable in one open end of the carton when the spreader member is advanced, said spreader fingers being engageable with the carton upon actuation thereof to spread the carton at said one open end in at least one direction to permit a plurality of articles to be received easily within the said open end of the carton, a retractable pusher movable to push a plurality of articles simultaneously from the article conveyor and into the said open end of the carton, said spreader fingers being engageable with the article during movement thereof into the carton to actuate the fingers and maintain the carton in spread condition during movement of the articles into the carton.

5. A cartoning machine for packaging articles in open-ended cartons comprising an intermittently movable carton conveyor for moving a series of open-ended cartons successively to a loading station, a movable article conveyor for moving a series of articles successively to a discharge position in register with a carton at said carton loading station, a retractable spreader member movable between advanced and retracted positions toward and away from the carton at said loading station, opposed spreader fingers movably mounted on the spreader member and receivable in one open end of the carton body when the spreader member is advanced, said spreader fingers being engageable with the carton upon actuation thereof to spread the carton at said one open end in at least one direction to permit a plurality of articles to be received easily within the said open end of the carton, a retractable pusher movable to push a plurality of articles simultaneously from the article conveyor and into the open end of the carton, said spreader fingers being engageable with the articles during movement thereof into the carton to actuate the same and maintain the carton in spread condition during movement of the articles into the carton, a second movable article conveyor for moving a series of articles successively to a discharge position in register with the carton at said carton loading station, a second retractable spreader member movable between advanced and retracted positions toward and away from the carton at said loading station, opposed spreader fingers on said latter spreader member and receivable in the other open end of the carton body when the spreader member is advanced, said lat-

ter spreader fingers being engageable with the carton upon actuation thereof to spread the carton at said latter open end to facilitate reception of an article from the second conveyor, a second retractable pusher for pushing an article from the second article conveyor into said latter open end of the carton, said latter spreader fingers being engageable with the articles during the movement thereof into the carton to actuate the same and maintain the carton in spread condition during movement of said latter article into the carton.

6. A packaging machine for packaging a plurality of articles in open-ended cartons comprising a movable carton conveyor to convey open-ended cartons successively to a loading station where articles are placed in the cartons from opposite ends thereof, means to move a plurality of articles successively to a discharge position in register with an open end of a carton at said station, means to move a plurality of articles from said discharge position simultaneously into said open end of a carton at said loading station, means engageable with the articles as they move into said open end to enter said carton body and to spread said open end of the carton while said articles are inserted therein, a second means to move a plurality of articles successively to a second discharge position in register with the other open end of said carton, means to move an article from said second discharge position into the other open end of said carton, and means engageable with said latter article as it moves into said latter open end to enter said carton body and to spread said latter open end of the carton as said article is inserted thereinto.

7. A packaging machine for packaging a plurality of articles in open-ended cartons comprising a movable carton conveyor to convey open-ended cartons successively to a loading station where articles are placed in the cartons from opposite ends thereof, a first movable article conveyor to move a plurality of articles successively to a discharge position in register with one open end of a carton at said station, means to insert simultaneously a plurality of articles from said discharge position into one open end of a carton at said loading station, means engageable with the articles as they move into said open end to enter said carton body and to spread said open end of the carton while said articles are inserted therein, a second movable article conveyor to move a plurality of articles successively to a second discharge position in register with the other open end of said carton, means to move a plurality of articles from said second discharge position into said other open end of said carton, and means engageable with said latter articles as they move into said latter open end of the carton to enter said carton body and to spread said latter open end of said carton while said latter articles are being inserted into the carton.

8. A packaging machine for packaging a plurality of articles in open-ended cartons comprising a movable carton conveyor to convey open-ended cartons successively to a loading station to have articles placed in the cartons, a first movable article conveyor for moving a series of articles successively to a discharge position in register with said carton, means to insert a plurality of articles from said article conveyor into one open end of a carton at said discharge position, yieldable means normally maintained out of contact with the carton and engageable with the articles as they move into the carton for en-

gaging the carton to spread said open end of said carton while said plurality of articles are inserted therein, a second movable article conveyor to move a series of articles successively to

- 5 a second discharge position at the other open end of said carton, means to insert a plurality of articles from said second conveyor into said latter open end of said carton, yieldable means normally maintained out of contact with the carton and engageable with the articles as they move into said latter open end of the carton for engaging the carton to spread said latter open end of said carton while said latter articles are being inserted simultaneously.
- 10 15. 9. A packaging machine for packaging a plurality of articles having depressed ends bounded by outstanding peripheral rims into containers each having inwardly extending opposed integral flaps on opposed walls of the container at each end and receivable in the depressions in the articles and abutting inner edges of the rims to hold the articles in the container, comprising a centrally disposed intermittently movable container conveyor to move said containers successively to a loading station, a first movable article conveyor located at one side of the container conveyor to deliver articles to a predetermined discharge position in register with a carton at said loading station, means to insert an article in one end of
- 20 30 a container at said loading station from the conveyor, means to spread the opposed walls of the container at one end thereof and to force the flaps on said end against the walls of the container as the article is being inserted, a second article conveyor on the other side of the container conveyor to deliver articles to a second discharge station in register with the carton at said second discharge station, means to insert an article into the other end of the container from the latter conveyor, and means to spread the opposed walls of the container at its said other end and to force the flaps on said other end against the walls of the container as the latter article is being inserted in said other end.
- 35 40 45 10. A packaging machine for packaging a plurality of articles having depressed ends bounded by outstanding peripheral rims into containers each having inwardly extending opposed integral flaps on opposed walls of the container at each end and receivable in the depressions in the articles and abutting inner edges of the rims to hold the articles in the container, comprising a centrally disposed intermittently movable container conveyor to move said containers successively to at least a first and second loading station, a first movable article conveyor located at one side of the container conveyor to deliver articles to a predetermined discharge station opposite the first container loading station, means to insert an article into one end of a container from the first discharge station at the first loading station, means to spread the opposed walls of the container at one end thereof and to force the flaps on said end against the walls of the container as the article is being inserted, a second article conveyor on the other side of the container conveyor to deliver articles to a predetermined discharge station opposite the second container loading station, means to insert an article into the other end of the container from the latter discharge station at the second container loading station, and means to spread the opposed walls of the container at its said other end and to force the flaps on said other end against the walls of the
- 50 55 60 65 70 75

11

container as the latter article is being inserted in said other end, said last named article inserting means shifting all of the articles in the container so as to position the articles at each end of the container with respect to the flaps at each end so that the flaps will be in registration with the rims of the end articles and thereby lock the articles to the container by the rims engaging the flaps.

11. A packaging machine for packaging a plurality of articles having depressed ends bounded by outstanding peripheral rims into containers each having inwardly extending opposed integral flaps on opposed walls of the container at each end and receivable in the depressions in the articles and abutting inner edges of the rims to hold the articles in the container, comprising a centrally disposed intermittently movable container conveyor to move said containers successively to at least a first and second loading station, means located at one side of the container conveyor to deliver articles to a predetermined discharge station opposite the first container loading station, means to insert an article into one end of a container from the first discharge station at the first loading station, means to spread the opposed walls of the container at said latter end thereof and to force the flaps on said end against the walls of the container as the article is being inserted, means on the other side of the container conveyor to deliver articles to a predetermined discharge station opposite the second container loading station, means to insert an article into the other end of the container from the latter discharge station at the second container loading station, and means to spread the opposed walls of the container at its said other end and to force the flaps on said other end against the walls of the container as the latter article is being inserted in said other end, said last named article inserting means shifting all of the articles in the container so as to position the articles at each end of the container with respect to the flaps at each end so that the flaps will be in registration with the rims of the end articles and thereby lock the articles to the container by the rims engaging the flaps.

12. A packaging machine for packaging a plurality of cans having depressed ends bounded by outstanding peripheral rims into containers which have inwardly extending opposed integral flaps on opposed walls of the container at each end thereof, the flaps being receivable in the depressions in the cans and adapted to abut the inner edges of the can rims to hold the cans in the container, comprising a centrally disposed intermittently movable container conveyor to move said containers successively to at least a first and a second loading station, means located at one side of the container conveyor to deliver cans to a predetermined discharge station opposite the first container loading station, means to insert two cans in one end of a container from the first discharge station while the container is at the first loading station, means to spread the opposed walls of the container at one end thereof and to force the flaps on said end against the walls of the container as the can is being inserted, and means to insert at least one can in the other end of the container, said inserting means operating to move said cans to a position where said flaps are received in said depressions.

13. A packaging machine for packaging a plurality of cans having recessed ends bounded by outstanding peripheral rims into containers which

12

have inwardly extending opposed integral flaps on opposed walls of the container at each end thereof and receivable in the recesses in the cans and adapted to abut the inner edges of the rims to hold the cans in the container, comprising a centrally disposed intermittently movable container conveyor to move containers successively to at least a first and a second loading station, a first movable can conveyor located at one side of the container conveyor to deliver cans to a first discharge station opposite the first container loading station, movable retractable pusher means to insert at least two cans in one end of a container from the first discharge station while the container is at the first loading station, movable retractable means to spread the opposed walls of the container at one end thereof and to force the flaps on said end against the walls of the container as the cans are being inserted, a second can conveyor located at the other side of the container conveyor to deliver cans to a discharge station opposite the second loading station, movable retractable pusher means to insert at least one can into the other end of the container from the latter discharge station when the container is at the second loading station, and movable retractable means to spread the opposed walls of the container at its said other end and to force the flaps on said other end against the walls of the container as said latter can is being inserted in said other end.

14. A packaging machine for packaging a plurality of cans having recessed ends bounded by outstanding peripheral rims into containers which have inwardly extending opposed integral flaps on opposed walls of the container at each end thereof and receivable in the recesses in the cans and adapted to abut the inner edges of the rims to hold the cans in the container, comprising a centrally disposed intermittently movable container conveyor to move containers successively to at least a first and a second loading station, a first movable can conveyor located at one side of the container conveyor to deliver cans to a first discharge station opposite the first container loading station, movable retractable pusher means to insert at least two cans in one end of a container from the first discharge station while the container is at the first loading station, movable retractable means to spread the opposed walls of the container at one end thereof and to force the flaps on said end against the walls of the container as the cans are being inserted, a second can conveyor located at the other side of the container conveyor to deliver cans to a discharge station opposite the second loading station, movable retractable pusher means to insert at least one can into the other end of the container from the latter discharge station when the container is at the second loading station, and movable retractable means to spread the opposed walls of the container at its said other end and to force the flaps on said other end against the walls of the container as said latter can is being inserted at said other end, said latter inserting means comprising a pusher to shift said cans to bring the recessed ends of the cans at the ends of the container into position with respect to the flaps so that the flaps will fall into the recessed ends and abut the inner edges of the rims of the end cans and lock the end cans to the container.

15. A packaging machine for packaging a plurality of cans having recessed ends bounded by outstanding peripheral rims into containers hav-

ing a length substantially less than the combined length of the cans to be packaged therein and which have inwardly extending opposed integral flaps on opposed walls of the container at each end thereof and receivable in the recesses in the cans and adapted to abut the inner edges of the rims to hold the cans in the container, comprising a centrally disposed intermittently movable container conveyor to move containers successively to at least a first and a second loading station, means located at one side of the container conveyor to deliver cans to a first discharge station opposite the first container loading station, movable retractable pusher means to insert at least two cans in one end of a container from the first discharge station while the container is at the first loading station, movable retractable means to spread the opposed walls of the container at one end thereof and to force the flaps on said end against the walls of the container as the cans are being inserted, means located at the other side of the container conveyor to deliver cans to a discharge station opposite the second loading station, movable retractable pusher means to insert at least one can into the other end of the container from the latter discharge station when the container is at the second loading station, and movable retractable means to spread the opposed walls of the container at its said other end and to force the flaps on said other end against the walls of the container as said latter can is being inserted at said other end, said latter inserting means comprising a pusher to shift said cans to bring the recessed ends of the cans at the ends of the container into position with respect to the flaps so that the flaps will fall into the recessed ends and abut the inner edges of the rims of the end cans and lock the end cans to the container.

16. The method of inserting cans having a recessed top and bottom defined by an outstanding peripheral annular rim into a container having a rectangular tubular body with open ends and integral flaps on the top and bottom at each end which comprises the steps of moving containers to a loading station, moving cans to a discharge station opposite the loading station, spreading the upper and lower walls of the container at one end, inserting a can in said end while the container is so spread, moving the container with a can therein to a second loading station, spreading the upper and lower walls of the container at its other end while at the second loading station, inserting another can in the other end of the container while the container is spread, and finally shifting all the cans in the container in a position so that flaps on the top and bottom of the container at each end thereof will be in registration with the recesses so that the flaps will engage the rims of the cans at each end of the container and lock the cans to the container.

17. A packaging machine for packaging a plurality of articles having depressed ends bounded by outstanding peripheral rims into containers each having inwardly extending opposed integral flaps on opposed walls of the container at each end and receivable in the depressions in the articles and abutting inner edges of the rims to hold the articles in the container, comprising a centrally disposed intermittently movable container conveyor to move said containers successively to at least a first and second loading station, a first movable article conveyor located at one side of the container conveyor to deliver ar-

ticles to a predetermined discharge station opposite the first container loading station, means to insert an article into one end of a container from the first discharge station at the first loading station, means to spread the opposed walls of the container at said latter end thereof and to force the flaps on said end against the walls of the container as the article is being inserted, a second article conveyor on the other side of the container conveyor to deliver articles to a predetermined discharge station opposite the second container loading station, means to insert an article into the other end of the container from the latter discharge station at the second container loading station, and means to spread the opposed walls of the container at its said other end and to force the flaps on said other end against the walls of the container as the latter article is being inserted in said other end.

18. A packaging machine comprising means to move an open-ended carton to a loading position, means to move an article to a discharge position in register with an open end of said carton at said loading position, arcuate spreader means pivotally mounted at one end and having the other end adapted to engage a portion of said carton and spread the same, the convex side of said arcuate portion of said spreader means being in the path of the article to be loaded into said carton, and means to push said article against the convex side of said spreader means and thence into said carton.

19. A packaging machine comprising means to move an open-ended carton to a loading position, means to move an article to a discharge position in register with an open end of said carton at said loading position, a pair of opposed spreader means yieldably mounted and having a portion thereof adapted to engage an article as it is loaded into said carton, an end of each of said spreader means being adapted to enter the body of said carton and to spread a panel of said carton when said article is loaded, and means to push said article against said spreader means and thence move an open-ended carton to a loading position into said carton.

20. A packaging machine comprising means to move an open-ended carton to a loading position with the end flaps turned downward in the path of an article to be loaded therein, means to move an article to a discharge position in register with an open end of said carton at said loading position, and spreader means actuated by said article as it moves into said carton, said spreader means operating to engage the flaps of the carton and push them into the body of the carton before the article enters the body of the carton.
